POWER TRANSMITTING MECHANISM

Rezin P. Kile, Riverton, Wyo.

Application June 25, 1935, Serial No. 28,307

6 Claims. (Cl. 192—139)

This invention relates to gearing and particularly to gearing whereby an awning, an advertising element, or endless element may be operatively connected to a motor so that the driven element may be alternately shifted in one direction or the other while the driving element operates always in the same direction.

A further object is to provide a mechanism of this character which is manually latched at the 10 termination of a movement in one direction and the power automatically disconnected and which, when the latch is released and the motor started, will automatically act to re-wind the driven element in the opposite direction for a predetermined time and then will automatically stop.

A further object is to provide a mechanism which, as illustrated, is particularly applicable to raising or lowering awnings and which is so constructed that the awning will not be torn under strain in case the awning has shrunk and which is so constructed that upon starting the mechanism in one direction, the awning will be rolled up and the mechanism locked in the wound-up position and which, when released, will automatically unroll the awning and stop when the awning has been completely unrolled.

Other objects will appear in the course of the following description.

My invention is illustrated in the accompanying drawings wherein:—

Figure 1 is a vertical section through the side wall of a building and through my winding mechanism;

Figure 2 is a fragmentary elevation of the mechanism shown in Figure 1;

Figure 3 is a fragmentary end elevation of one of the drum shafts, the drum thereon, the cylinder supporting the shaft and the sliding yoke upon which the shaft is carried;

Figure 4 is a fragmentary diagrammatic view illustrating the means whereby the motor is automatically stopped and started;

Figure 5 is a longitudinal sectional view upon the line 5—5 of Figure 2;

Figure 6 is a top plan view of the plate upon which the bearing for the shafts slides;

Figure 7 is a fragmentary section through one of the drums taken at right angles to the axis of rotation of the drum.

Referring to these drawings, 10 designates a base plate which is illustrated as disposed in a vertical position against the vertical wall "A" of a building. Brackets 11 extend outward from this base plate and support a winding shaft 12

upon which the awning 13 is assumed to be wrapped or rolled. The shaft has a friction clutch engagement with a stub shaft 14 which carries the gear wheel 15. This friction clutch 16 which may be of any suitable or usual construction is illustrated as including two discs frictionally bearing against each other and urged into frictional engagement by means of a spring.

As before stated, the purpose of this invention is to provide motor operated manually controllable means whereby an awning shaft or a shaft of the like general character may be rotated first in one direction and then in the other, for instance, to unroll or roll up the awning to thus avoid the necessity of manually rolling up or un- 15 rolling the awning or rotating a shaft.

To this end, I mount upon the base 10 the driving gear shaft 17, which is driven from the motor 18 in any suitable manner. I have illustrated for this purpose reducing gears 19 be- 20 tween the motor and the shaft 17, but it is to be understood that the shaft 17 might be driven by a belt upon the motor or by any other gearing system.

On shaft 17 is disposed a gear wheel 20 having exterior teeth 21 and internal teeth 22. This is the driving gear wheel. Opposite to the driving gear wheel 20 is a parallel driven gear wheel 23 having external teeth 24 and internal teeth 25. This gear wheel is also provided with laterally disposed external teeth 26 for a purpose to be later stated. This driven gear wheel 23, therefore, has internal teeth and two series of external teeth. The teeth 24 mesh with the pinion 15 on the winding shaft 12.

The gear wheel 23 is mounted on a shaft 27 which is in axial alignment with the shaft 17 and the internal gear teeth 25 and the internal gear teeth 22 have the same internal diameter.

Mounted for sliding movement, as will be later described, upon the outwardly projecting brackets 28 is a transmission shaft 29 which extends transversely across the space between the gear wheels 23 and 20, and mounted on brackets 30 is a second transmission shaft 31, which is parallel to the shaft 29. The shaft 31 carries upon it the pinions 38 which engage respectively with the internal gear wheels 22 and 25. The shaft 21 carries at one end a pinion 39 engageable with the external gear teeth 21 and at the other end a pinion 39^a which is engageable with an intermediate pinion 40 in turn engaging with the teeth 26. A rotation of the shaft 17 in one direction transmitted through the shaft 29 to the gear 55

wheel 23 will cause a rotation of this gear wheel in one direction, whereas if the shaft 31 be engaged with the gear teeth 21 and with the intermediate 40, the rotation of the gear wheel 22 in the same direction as before will cause a reverse rotation of the gear wheel 23 and, of course, a reverse rotation of the shaft 12.

The shafts 29 and 31 are each supported upon outstanding brackets 28 and 30, as before stated, and each of these brackets carries upon its outer end a plate 32, shown in Figures 5 and 6. Slidably mounted upon the opposite plates 32 of the brackets 28 is a transversely extending downwardly bowed yoke 51 and slidably mounted upon the plates 32 carried by the brackets 30 is a transversely extending downwardly bowed yoke 51^a. Each of these yokes carries upon it at its ends the bearing boxes 33 in which the respective shafts 29 and 31 are supported. Each of the yokes at its ends has downwardly extending bolts 35 which are slidably mounted in slots 34 formed in the respective plates 32 and anti-friction rollers 36 are disposed between the inner faces of the yokes and the outer faces of the plates 32, as shown in Figure 5. Thus it will be seen that the ends of the yokes 51 and 51^a together with the bearing boxes 33 are slidable over the outer faces of the corresponding plates 32.

These yokes with their bearing boxes are urged upward in Figure 1 by means of the springs 37 which bear against flanges 32^a on the lower ends of the plates 32. Thus this shaft 29 is urged by the corresponding springs 37 toward meshing engagement with the internal gears 22 and 25, while the shaft 31 is urged by the springs 37 into meshing engagement with the external teeth 21 and the teeth on the intermediate pinion 40.

Mounted upon the shaft 29 is a drum designated generally 41 and mounted upon the shaft 31 is a drum 42. Both drums are exactly alike. Each drum is expandable and contractible, that is, includes longitudinally extending slats 43 held by adjusting screws 44 to the core 45 of the drum, as illustrated in Figure 7. By turning these adjusting screws 44 in one direction or the other, the slats may be shifted radially outward or radially inward to thus control the effective diameter of the drum and thus adjust it for various lengths of awning, as will hereafter more fully appear. I do not wish to be limited to the particular means for increasing or decreasing the effective diameter of the drum, as other means might be used for this purpose, and the illustration which I have given merely shows one way in which the drums may be expanded or contracted.

Attached by its opposite ends to the drums so as to wrap therearound is a cable 46 which is designed to be alternately wrapped first partly around one drum and then wrapped partly around the other drum. This cable is attached to drum 41 and then passes from this drum outward and downward to a block or pulley 47 and then upward to the other drum to which it is attached, as shown in Figure 1. This block 47 is retracted downward and outward by a normally un-tensioned contractile spring 48 connected to a turnbuckle 49 in turn carried by an outstanding bracket or post 50.

Ordinarily, the spring 48 exerts no tension on cable 46, but when the cable has been entirely wound up on one drum, as shown in Figure 1, the cable will tighten because it can no longer unroll

off the other drum and this puts the spring 48 under tension. This tension will increase until it becomes so great as to draw the drum upon which the cable has been wound up and its shaft in a direction away from the teeth with which the pinions on this drum or transmission shaft coat, which is the position shown in Figure 1.

Each yoke 51 at its middle is depressed, as at 52, this depressed portion having an aperture 53 to receive the extremity of a latch 54. This latch 10 is pivoted as at 55, upon a supporting bracket 56. Each latch has an arm 57 which extends inward and is connected to an operating rod. One of these operating rods for one latch is designated 58 and the other rod is designated 15 58^a. Each latch has an outwardly extending arm 59 and to the extremity of this arm is connected a contractile spring 60 which at its lower end is mounted in a support 61. This spring moves past the center 55 for the corresponding latch so that 20 when the latch is in, that is, in the position shown in Figure 1 for the lower latch, the spring holds this latch in the aperture 53, and when the latch is thrown out, as is shown in Figure 1 for the upper latch, the spring will hold the latch 25 out. The rods 57 and 58 extend downward through suitable tubes or pipes or other passageways formed in or on the building and are provided with handles whereby they may be operated either from the interior of the building or 30 from the exterior.

The electric motor 18, as shown in Figure 4, is connected to a source of current through a switch having the two switch points 62 and 63. These switch points, as illustrated in Figure 4, 35 are resilient and they coat with a fixed switch point 64 which is connected to a battery 65. The line then runs from this battery to the motor 66 and then to the bed plate which supports the switches 62 and 63. When both of the contacts 40 62 or 63 are out of engagement with the contact 64, the circuit through the motor is broken. Bearing against these contacts are the rods 67 and 68. Rod 67 is connected to a lever 69, the other end of which is engaged by a fork 70 carried by 45 the yokes 51. The opposite rod 68 is connected to a lever 71 which in turn is engaged by a fork carried by the other yoke 51^a. When a yoke is shifted by its springs 37 into engagement with the driving and driven gear wheel, the corresponding rods 67 and 68 will force the corresponding contact finger 62 or 63 into engagement with the central contact and close the circuit through the motor. The motor will then start, causing a rotation of the proper shaft 29 or 31 55 which will cause a rotation of the driven gear wheel 23 to in turn cause either a rotation of the shaft 12 to roll up the awning or a rotation of the shaft which will unroll the awning. The switch is illustrated as being enclosed within a 60 switch box or casing 72. In Figure 4, the switch is shown as being closed by the movement of the yoke 51 to carry the shaft 29 into operative engagement with the internal teeth 22, but it is to be understood that in the positions shown in 65 Figures 1 and 2, which are neutral positions, the contacts 62 and 63 are both disengaged from the contact 64.

The purpose of providing the clutch 16 between the shaft section 12 and the shaft section 12^a 70 is to permit the shaft section 12^a to continue to operate after the shaft section 12 has been stopped by the complete unrolling or rolling up of an awning. The awning may shrink and, therefore, though the mechanism which has been 75

described might initially be adjusted so as to stop when the awning is fully rolled up or stop when the awning has been fully unrolled, yet after the awning shrinks, it would be likely to tear if the clutch 16 were not provided.

The cable 46 has the same length as the awning to be rolled or unrolled and stops the mechanism when this cable has been wound up entirely upon one drum or entirely upon the other drum. The purpose of providing expandable and contractible drums is to increase or decrease the number of rotations which will be necessary to wind up this cable and, therefore, wind up the awning or unwind it, and by adjusting the diameter of these drums, provision may be made for taking up any slack which might occur in the cable or in the awning.

The operation of this mechanism is as follows: As illustrated in Figures 1 and 2, the awning 13 has been fully lowered. The transmission shaft 29 has been automatically drawn out of its engagement with the internal gear teeth 22 and 25, the electric current has broken through the motor 66 and the mechanism is stopped, the yoke 51^a being locked by its corresponding latch 54, as shown in Figure 1. Now if it be desired to wind up the awning, the latch 54 of the yoke 51^a is released. Under these circumstances, the springs 37 of yoke 51^a will urge the yoke upward to carry the pinions 39 and 39^a into engagement with the teeth 21 and the pinion 49, respectively. This movement of the yoke 51^a will close the circuit through the motor and the motor will rotate the gear wheel 28, the transmission shaft 31 transmitting this rotation to the gear wheel 23 by means of the teeth 25 and rotating the shafts 12^a and 12 in a direction to roll up the awning. This action will cause the cable 46 to roll up upon the drum 42 and unwind from the drum 43. When the cable has completely unwound from the drum 43, the further winding movement of the drum 42 will cause the cable to place the spring 48 under tension and this, as the tension increases, will pull the yoke 51^a downward automatically disengaging the gears 39 and 39^a from the teeth 21 and the pinion 49 and automatically breaking the circuit through the motor. The cable 46 is of such length that this stoppage will occur when the awning has been completely wound up. As soon as this has been done, the operator locks the yoke 51^a in its retracted position. Now if he wishes to unroll the awning, he releases the latch 54 for yoke 51; the springs 37 then shift the yoke 51 to carry the pinions into engagement with the internal gears 22 and 25 and this action through the switch automatically starts the motor. A rotation reverse to the former rotation is thus given to the gear wheel 23 and to the shafts 12^a and 12, and the awning 60 is unwound. As soon as the awning has been completely unwound, the cable 46 is completely unwound from the drum 41 and then the tension of the spring 48 acts to pull back down the yoke 51 from the shaft 29 to thus release the driving connection between the driving gear 21 and the transmission shaft and between the transmission shaft and the driven gear 23. It will thus be seen that the action is automatic in that after the one or the other of the latches has been lifted, 70 the motor immediately commences to drive the shaft 12 in one direction or the other and that this driving motion is stopped as soon as the shaft 12 or the driven shaft 29 has made a predetermined number of rotations.

75 While I have illustrated my mechanism as ap-

plied to an awning shaft, I wish it distinctly understood that this transmission mechanism might be used wherever it is desired to rotate a shaft such as the shaft 15 first in one direction and then in the other, and that this shaft 15 might be used for driving any desired mechanism such as advertising devices, elevator shafts or any mechanism which is driven first in one direction and then in the other.

What is claimed is:—

1. In a mechanism of the character described, an electric motor, a driving shaft operably connected to the motor to be driven thereby, a driven shaft, two transmission shafts disposed between the driving and the driven shafts and normally out of engagement with the driving and driven shafts, one of the two transmission shafts being engageable with the driven shaft to drive it in one direction, the other being engageable with the driven shaft to drive it in the other direction, means urging the two shafts into operative engagement with the driving and driven shafts, manually releasable means for locking each of said shafts out of said driving engagement against the action of said urging means but releasable to allow the corresponding shaft to move into operative engagement with the driving and driven shaft under the action of said urging means, and means automatically withdrawing that transmission shaft which has been operatively engaged with the driving and driven shafts from said engagement when the driven shaft has made a predetermined number of revolutions.

2. In a mechanism of the character described, an electric motor, a driving shaft connected to the motor, a gear wheel on the driving shaft having internal and external teeth, a driven shaft in alinement with the driving shaft, a gear thereon having internal and external teeth, two transmission shafts extending between the gear wheels on the driving and driven shafts, one of said transmission shafts having pinions thereon engaging with the internal teeth of both the driving and the driven shafts, the other of said transmission shafts having at one end a pinion engaging the external teeth of the driving gear wheel and at the other end having a pinion, an intermediate gear wheel between said last named pinion and the external gear teeth of the driven gear wheel, means urging the two transmission shafts in a direction to carry their pinions into engagement with the driving and driven gear wheels, manually releasable means locking both shafts for movement under the action of said urging means but releasable to permit either transmission shaft to move in a direction to carry its pinions into operative engagement with the driving and driven shafts under the action of said urging means, and means automatically withdrawing that transmission shaft whose pinions have been operatively engaged with the driving and driven gear wheels from said engagement when the driven gear wheel has made a predetermined number of revolutions.

3. In a mechanism of the character described, an electric motor, a driving shaft connected to the motor, a gear wheel carried thereon having external and internal teeth, a driven shaft in alinement with the driving shaft, a driven gear wheel thereon having external and internal teeth, two transmission shafts extending transversely across the space between the driving and driven gear wheels, one of said shafts having pinions at its ends engaging with the internal teeth of the driving and driven gear wheels, the other of

said transmission shafts having pinions on its ends, one pinion being engageable with the external teeth of the driving gear wheel, an intermediate gear wheel engaging the exterior teeth 5 of the driven gear wheel and engaging the pinion on that end of the last named transmission shaft, a drum on each of the transmission shafts, a cable attached at its ends to said drums, the cable being of such length that when it is wound a predetermined amount upon one drum it will be entirely unwound from the other drum, means supporting the ends of the transmission shafts for sliding movement toward or from the gear teeth on the driving and driven gear wheels, means 10 urging each of said transmission shafts toward the teeth with which its pinions engage, manually releasable means for locking each of said transmission shafts out of driving engagement with the driving and driven gear wheels and against the action of said urging means, said locking means being releasable to allow the corresponding shafts to move into said operative engagement with the driving and driven gear wheels under the action of its urging means, and 15 a pulley over which the cable passes, a normally untensioned spring engaging the pulley and urging said pulley away from both drums, said spring when under tension withdrawing either transmission shaft from its engagement with the teeth on the driving and driven gear wheels whereby when the cable is completely wound off of one drum and wound upon the other drum, said spring will be placed under tension and automatically shift the shaft of the operating drum 20 out of its driving engagement.

4. In a mechanism of the character described, an electric motor, a driving shaft connected to the motor, a gear wheel carried thereon having external and internal teeth, a driven shaft in alignment with the driving shaft, a driven gear wheel thereon having external and internal teeth, two transmission shafts extending transversely across the space between the driving and driven gear wheels, one of said shafts having pinions at its 25 ends engaging with the internal teeth of the driving and driven gear wheels, the other of said transmission shafts having pinions on its ends, one pinion being engageable with the external teeth of the driving gear wheel, an intermediate gear wheel engaging the exterior teeth of the driven gear wheel and engaging the pinion on that end of the last named transmission shaft, a drum on each of the transmission shafts, a cable attached at its ends to said drums, the cable being of such length that when it is wound a predetermined amount upon one drum, it will be entirely unwound from the other drum, means supporting the ends of the transmission shafts for sliding movement toward or from the gear teeth on the driving and driven gear wheels, means urging each of said transmission shafts toward the teeth with which its pinions engage, manually releasable means for locking each of said transmission shafts out of driving engagement with the driving and driven gear wheels and against the action of said urging means, said locking means being releasable to allow the corresponding shafts to move into said operative engagement with the driving and driven gear wheels under the action of its urging means, means actuated by said cable when completely unwound from one drum acting automatically to retract the shaft of the other drum from its operative engagement with the driving and driven gear wheels, and means actuated by the retraction of 50

said shaft automatically cutting off current to the motor and by the projection of said shaft into driving engagement with the driving and driven gear wheels upon the release of the locking means acting to close the circuit through the motor. 5

5. In a mechanism of the character described, an electric motor, a driving shaft operatively connected to the motor, a driven shaft in alignment with the driving shaft, a gear wheel on the driving shaft having external and internal teeth, a gear wheel on the driven shaft having external and internal teeth, an operating shaft driven by the external gear teeth of the driven gear wheel, two transmission shafts extending between the driving and the driven gear wheels, a yoke for each shaft and having bearings at its ends for the shaft, brackets slidingly supporting the ends of each yoke, pinions mounted upon the ends of one transmission shaft and engaging the internal gear teeth of the driving and driven gear wheels, pinions carried upon the ends of the other transmission shaft, one of said pinions being engageable with the external teeth of the driving shaft, an intermediate gear wheel engaging the external teeth of the driven gear wheel and engaging the other pinion on the last named transmission shaft, springs urging both of said yokes in a direction to carry the pinions on their respective shafts into engagement with the gear teeth with which said pinions coact, a drum mounted upon each transmission shaft, each drum being adjustably expansible and contractible, a cable attached at its ends to each drum, the cable having a length such that when wound a predetermined amount upon one drum, it will be entirely unwound from the other drum, manually operable locking means for each yoke and adapted to lock the yoke with the pinions on its shaft in operative engagement with the teeth on the driving and driven gear wheels with which 40 said pinions coact, springs urging said yokes in a direction to carry their shafts into operative engagement with the coacting teeth on the driving and driven gear wheels when said locking means is released, means engaged by said cable and acting automatically when the cable has been entirely withdrawn from one drum to exert a retractile force on the other drum to thus retract the yoke of this drum against the action of said springs to thereby carry the shaft of said yoke 50 out of operative engagement with its corresponding gear teeth and a switch operative to break an electrical circuit through the motor when either transmission shaft has been shifted out of engagement with the corresponding gear teeth on 55 the driving and driven gear wheels and automatically shiftable to close said circuit when either yoke has been shifted to carry its shaft into operative engagement with the corresponding gear teeth on the driving and driven gear wheels. 60

6. In a mechanism of the character described, an electric motor, a driving shaft operatively connected to the motor, a driven shaft in alignment with the driving shaft, a gear wheel on the driving shaft having external and internal teeth, a gear wheel on the driven shaft having external and internal teeth, and operating shaft driven by the external gear teeth of the driven gear 70 wheel, said operating shaft being formed in two sections and a friction clutch connection between the two sections, two transmission shafts extending between the driving and the driven gear wheels, a yoke for each shaft and having bear- 75

ings at its ends for the shaft, brackets slidingly supporting the ends of each yoke, pinions mounted upon the ends of one transmission shaft and engaging the internal gear teeth of the driving 5 and driven gear wheels, pinions carried upon the ends of the other transmission shaft, one of said pinions being engageable with the external teeth of the driving shaft, an intermediate gear wheel engaging the external teeth of the driven gear 10 wheel and engaging the other pinion on the last named transmission shaft, springs urging both of said yokes in a direction to carry the pinions on their respective shafts into engagement with the gear teeth with which said pinions coat, a drum 15 mounted upon each transmission shaft, each drum being adjustably expansible and contractible, a cable attached at its ends to each drum, the cable having a length such that when wound a predetermined amount upon one drum, it will be 20 entirely unwound from the other drum, manually operable locking means for each yoke and adapted to lock the yoke with the pinions on its shaft in operative engagement with the teeth on the

driving and driven gear wheels with which said pinions coat, springs urging said yokes in a direction to carry their shafts into operative engagement with the coacting teeth on the driving and driven gear wheels when said locking means 5 is released, means engaged by said cable and acting automatically when the cable has been entirely withdrawn from one drum to exert a retractile force on the other drum to thus retract the yoke of this drum against the action of said 10 springs to thereby carry the shaft of said yoke out of operative engagement with its corresponding gear teeth, and a switch operative to break an electrical circuit through the motor when either transmission shaft has been shifted out of 15 engagement with the corresponding gear teeth on the driving and driven gear wheels and automatically shiftable to close said circuit when either yoke has been shifted to carry its shaft into operative engagement with the correspond- 20 ing gear teeth on the driving and driven gear wheels.

REZIN P. KILE.
